DESIGN FOR A TANK VEHICLE

George A. Brasfield, Berkeley, Calif.

Application May 9, 1947, Serial No. 138,948

Term of patent 7 years

(Cl. D14—3)

To all whom it may concern:

Be it known that I, George A. Brasfield, a citizen of the United States of America and a resident of the city of Berkeley, county of Alameda, State of California, have invented a new, original, and ornamental Design for a Tank Vehicle, of which the following is a specification, reference being had to the accompanying drawing, forming a part thereof.

Figure 1 is a side elevational view of a tank vehicle, showing my new design;

Figure 2 is a plan view of the tank vehicle;

Figure 3 is an elevational view of the front end of the tank vehicle;

Figure 4 is an elevational view of the rear end of the tank vehicle.

I claim:

The ornamental design for a tank vehicle, substantially as shown.

GEORGE A. BRASFIELD.
